UNITED STATES PATENT OFFICE.

FRANK E. CASE, OF SCHENECTADY, NEW YORK, ASSIGNOR TO GENERAL ELECTRIC COMPANY, A CORPORATION OF NEW YORK.

PANTOGRAPH-TROLLEY.

963,865.

Specification of Letters Patent. Patented July 12, 1910.

Application filed February 25, 1909. Serial No. 479,917.

To all whom it may concern:

Be it known that I, FRANK E. CASE, a citizen of the United States, residing at Schenectady, county of Schenectady, State of New York, have invented certain new and useful Improvements in Pantograph-Trolleys, of which the following is a specification.

This invention relates to electric railways, and its object is to provide an improved pantograph trolley for high speed electric vehicles.

It has been found that when an electric car runs at speeds of forty miles an hour or over, the traveling contact, whether wheel or roller, has a tendency to separate from the wire at the high points or where the wire is higher than usual, as for instance at the span wires or other supports. This tendency is corrected to some extent by the catenary method of suspension, but even this does not wholly cure the trouble. When alternating currents of high tension are used on the working conductor, this breaking of the circuit so frequently produces a destructive effect on the insulation of all electrified parts and when heavy direct currents are used on the working conductor the breaking of the current effects a rapid deterioration of collector and trolley wire, and the purpose of my invention is to prevent the trouble by so constructing the trolley as to render it quite unlikely that the current collector will leave the wire. I accomplish this by mounting the traveling contact on a short light support which is pivoted to the trolley framework on a horizontal transverse axis, so that it can swing forward and backward; and then providing springs which tend to hold said support in an upright position, but which permit it to yield independently of the up and down movements of the trolley framework; thereby causing the traveling contact to follow the wire more closely than the inertia of the trolley framework will permit. In order to economize material and simplify the construction I utilize for this purpose the same springs which are employed to lift the pantograph framework.

In the accompanying drawings, Figure 1

is a side elevation, partly in section, of a pantograph trolley embodying my improvements, the trolley being shown in the depressed position it occupies when out of service; Fig. 2 shows the same trolley raised for service; Fig. 3 is a top plan view of the central portions of said trolley; and Fig. 4 is an end elevation of said trolley.

In the main, this trolley is similar to those now in use, consisting of two parallel transverse shafts 1 1' journaled in suitable bearings 2 2' mounted on top of the electric car or other vehicle. Each shaft carries at or near its ends the arms 3 3' to whose outer ends are pivoted the cross shafts 4 4' on which are mounted the arms 5 5', connected at their upper ends to the transverse rod 6 and stiffened by the diagonal braces 7. The rod 6 is common to both sets of arms 5 5' so that the entire structure constitutes a toggle. The two shafts 1 1' are cross connected by rock arms 8 8' and links 9 so that both must rotate in unison and compel both sides of the toggle to rise and fall together.

Pivoted on the rod 6 are the uprights or standards 10 on whose upper ends is supported the traveling contact, such as the roller 11 having gudgeons journaled in said standards. Guard fingers 12 may extend outwardly and downwardly from the upper ends of the standards. In order to maintain the standards yieldingly upright, the links 13 13' are pivoted to them and serve to connect them to short levers 14 14' fulcrumed on the cross shafts 4 4'. To the opposite ends of these levers are attached the springs 15 15' whose other ends are secured to the arms 3 3'; preferably by means of the brackets 16 16' bolted to said arms and carrying nuts in which mesh tension screws 17 17' to which the ends of the springs are fastened, and by means of which the tension of said springs can be adjusted.

The pull exerted by the springs is adjusted so that those on one side of the toggle balance those on the other side, and thus the standards are kept normally in an upright position, as shown. Nevertheless, the contact can move forward or backward relative

to the axis 6, when any undue stress is applied to it sufficient to overcome the tension of the spring which opposes this movement, and which constantly tends to return the 5 roller standards to their vertical position. Inasmuch as the inertia of these parts is slight compared with that of the entire trolley structure, this construction provides for an independent action of the roller and 10 its standards 6 enabling it to follow closely the undulations of the trolley wire and effectually preventing any flashing between said wire and the traveling contact at high speed. Moreover, it will be noticed that the 15 springs 15 15' tend to urge the trolley upward, so that when released from its collapsed position it will rise automatically until the roller makes contact with the wire. In other words, these springs perform two 20 functions; that of lifting the trolley and keeping the roller pressed against the wire, and that of allowing the roller to have a to and fro movement independent of the main trolley structure.

25 The means for retracting the trolley comprise a long horizontal cylinder 18 placed lengthwise of the car between the transverse shafts 1 1'. In this cylinder are two pistons 19 19' connected respectively to the rock 30 arms 20 20' on the two shafts 1 1'. When fluid pressure is admitted between the two pistons they are forced apart and turn the shafts swinging the arms 3 3' down to the position shown in Fig. 1, and permitting 35 the upper members of the toggle to drop until the joint at the rod 6 passes below the dead center or below the plane of the joints at 4 and 4'. Upon releasing the fluid pressure the trolley parts remain locked in this 40 position, so that no expenditure of energy is required to hold them while the trolley remains out of service.

When it is desired to raise the trolley, a small kicking-off device is employed, such 45 as the cylinder 21 containing a piston 22 which is connected by the rod 23 with an elbow lever 24, whose long arm lies under the joint of the toggle. Upon admitting fluid pressure to this cylinder, the lever is 50 thrown up and kicks up the joint of the trolley past the dead center, after which the springs 15 15' raise the trolley, as before described. As the roller goes up, the pistons 19 19' approach each other and by 55 compressing the air in the cylinder 18 effect a cushioning of the parts which prevents injurious shock.

I do not desire to restrict myself to the particular form or arrangement of parts 60 herein shown and described, since it is apparent that they may be changed and modified without departing from my invention.

What I claim as new and desire to secure by Letters Patent of the United States, is,

1. A pantograph trolley having its traveling contact capable of vibratory movement independent of the pantographic structure, and a single set of springs operating to raise the trolley and also to maintain the contact yieldingly in a normal position. 65

2. A pantograph trolley having its traveling contact capable of movement to and fro independent of the pantographic structure, and a single set of springs adapted to raise the trolley and also maintain said contact yieldingly in a normal position. 70

3. A pantograph trolley having pivoted standards rising from its upper joint, a traveling contact mounted on said standards, springs for raising the trolley, and connections between said springs and said standards. 80

4. A pantograph trolley having its traveling contact capable of movement forward and backward with reference to the pantographic structure, lifting springs mounted on the lower arms of the pantograph, and connections between said springs and said contact. 85

5. A pantograph trolley having its traveling contact mounted on supports capable of forward and backward movement with reference to the pantographic structure, lifting springs mounted on the lower arms of the pantograph, levers to which said springs 90 are connected, and links connecting said levers with the supports of said contact. 95

6. In a pantograph trolley, the combination with the lower arms thereof, of levers pivoted at the outer ends of said arms, 100 springs attached at one end to said arms and at the other to the lower ends of said levers, upright standards pivoted at the upper joint of the pantograph, a traveling contact mounted on said standards, and links connecting said standards with the upper ends of said levers. 105

7. In a pantograph trolley, the combination with the upper and lower arms thereof, of levers pivoted to the outer ends of said arms, springs for biasing said levers, a contact member pivoted at the upper joint of the pantograph, and connecting links connected to said levers and to said contact member and paralleling the upper arms. 110 115

8. In a pantograph trolley, the combination with the upper and lower arms thereof, of levers pivoted to the outer ends of said arms, springs for biasing said levers, a contact member pivoted at the upper joint of the pantograph, connecting links connected to said levers and to said contact member and paralleling the upper arms, and means for depressing the upper joint of the pantograph below the plane of the outer joints 120 thereof. 125

9. In a pantograph trolley, the combination with the upper and lower arms thereof,

of levers pivoted to the outer ends of said arms, springs for biasing said levers, a contact member pivoted at the upper joint of the pantograph, connecting links connected to said levers and to said contact member and paralleling the upper arms, means for depressing the upper joint of the pantograph below the plane of the outer joints

thereof, and kick off means for restoring said pantograph to operative position. 10

In witness whereof, I have hereunto set my hand this 23rd day of February, 1909.

FRANK E. CASE.
